UNITED STATES PATENT OFFICE

124,295

DESIGN FOR A COMBINATION CALENDAR- DESK UNIT

George G. Taubert, Pittsfield, Mass., assignor to
General Electric Company, a corporation of
New York

Application August 28, 1940, Serial No. 94,678

Term of patent 14 years

To all whom it may concern:

Be it known that I, George G. Taubert, a citizen
of the United States, residing at Pittsfield, in
the county of Berkshire, Commonwealth of
Massachusetts, have invented a new, original,
and ornamental Design for a Combination Cal-
endar-Desk Unit, of which the following is a
specification, reference being had to the accom-
panying drawing, forming a part thereof.

In said drawing:

Figure 1 is a view in perspective of a combi-
nation calendar-desk unit showing my new design.

Figure 2 is a rear view.

The printed matter shown in Figure 1 of the
drawing is merely representative in character.

I claim:

The ornamental design for a combination cal-
endar-desk unit, as shown and described.

GEORGE G. TAUBERT.
